Primary Examiner — Jack Reickel*Assistant Examiner* — Keith J Wilson(74) *Attorney, Agent, or Firm* — Kinney & Lange, P.A.(57) **CLAIM**

The ornamental design for a component mixing chamber, as shown and described.

DESCRIPTION

FIG. 1 is a perspective view a component mixing chamber; FIG. 2 is a front elevational view of the component mixing chamber;

FIG. 3 is a rear elevational view of the component mixing chamber;

FIG. 4 is a left side view of the component mixing chamber; FIG. 5 is a right side view of the component mixing chamber;

FIG. 6 is a top view of the component mixing chamber; and, FIG. 7 is a bottom view of the component mixing chamber. The broken lines shown represent portions of a component mixing chamber and form no part of the claimed design.
